UNITED STATES PATENT OFFICE.

PAUL J. DAHM, OF FORT WAYNE, INDIANA.

ROOF AND METHOD OF LAYING THE SAME.

Application filed June 12, 1925. Serial No. 36,632.

To all whom it may concern:

Be it known that I, PAUL J. DAHM, a citizen of the United States, residing at Fort Wayne, in the county of Allen and 5 State of Indiana, have invented new and useful Improvements in Roofs and Methods of Laying the Same, of which the following is a specification.

The invention relates to the art of laying shingles and its object is to provide a novel method of laying interlocking shingles whereby they are positively locked in position and can neither curl or be turned up by the wind.

10 The invention consists in a shingle having a slot in one corner in which slot the next adjacent shingle is engaged so that the adjacent shingle overlaps the first shingle below the slot and underlaps the portion 20 thereof above the slot.

An embodiment of the invention is illustrated in the accompanying drawings in which

Figure 1 is a plan view of a shingle constructed in accordance with the invention and Fig. 2 a plan view of a section of a roof having the shingles thereon laid in accordance with my invention.

15 The shingle 1 is formed of any suitable flexible or pliable material and in any desired size and shape, the rectangular form shown being illustrative only. A slot 2 is formed in one corner of the shingle and extends inwardly from one edge of the shingle preferably at a selected angle toward the adjacent edge. Preferably an opening 3 is formed in the shingle at the inner end of the slot to form a guide in applying the next shingle and providing 20 space for horizontal expansion or contraction.

In Fig. 2 the method of laying the shingles is illustrated. Each shingle is 45 formed with the slot 2 and the aperture 3 as in Fig. 1. The view illustrates a section of a roof at the lower left corner thereof, so that along the left edge alternate shingles 4 are substantially half as wide as the remainder thereof. In laying the shingles one 50 of the shingles 1 is fit at the corner of the roof and a nail or other suitable device 5 is driven through the section 6 below the slot 2 and into the supporting material below. A second shingle 1^a is then inserted 55 under the right side of the shingle 1 and

in the slot 2 until the left edge of the shingle 1^a abuts the end of the slot or the wall of the aperture 3. A nail or other securing means 7 is then driven through the overlapping edges of the two shingles above 60 the slot, the operation being continued across the roof. It will be noted that the shingle 1^a overlaps the section 6 of the shingle 1, covering the securing means 5, and underlaps the portion of the edge of the shingle 1 that is above the slot. The first shingle 4 of the second course is laid on the shingle 1 at the selected distance above the lower edge of the shingle 1 and the section 6 thereof is secured as before described. A shingle 1 is then inserted under the right edge of the shingle 4 and in the slot and a nail 7 is driven through the overlapping portions of the two shingles. The roof is entirely 70 covered in this manner and each shingle is firmly locked to its neighbor so that the lower edge will not turn up or curl up, one lower corner of each shingle being securely held by its overlapping neighbor and the other lower corner being held by the fastening means. At the same time all nails in any shingle are covered up by the shingle that overlaps it so that water and snow cannot reach them. However, the shingles may 75 be of such size and so laid to the weather that some of the nails may be exposed.

The edges 8 of the shingles of each transverse course are substantially in alinement with the corresponding edges of the shingles in each of the other courses so that the completed roof is very attractive and neat in appearance.

The shingles, as shown at 9, in Fig. 2, may be of such size and arrangement that three of them overlap, thus affording additional security against leaking and adding to the rigidity on the roof.

What I claim is:

1. A roof including a base and shingles laid thereon in horizontal rows, each of said shingles being of uniform size and rectangular contour, the shingles being laid with their bottom edges horizontal and their side edges vertical, the bottom edges of the shingles in each row being horizontally 100 alined, each shingle having a single diagonal slit extending from a point on one side edge adjacent the bottom edge downwardly and inwardly of the shingle, the remaining side 105 edge of each shingle being continuous and 110

being inserted in the slit of the laterally adjacent shingle with the part below the slit underlying the inserted edge.

2. A roof including a base and shingles laid thereon in horizontal rows, each of said shingles being of uniform size and rectangular contour, the shingles being laid with their bottom edges horizontal and their side edges vertical, the bottom edges of the shingles in each row being horizontally aligned, each shingle having a single diagonal slit extending from a point on one

side edge adjacent the bottom edge downwardly and inwardly of the shingle, the remaining side edge of each shingle being continuous and being inserted in the slit of the laterally adjacent shingle with the part below the slit underlying the inserted edge, the shingles in one row being arranged in staggered relation to the shingles in the adjacent row.

In witness whereof I have hereunto set my hand this 8th day of June, 1925.

PAUL J. DAHM.
